(57) **CLAIM**

The ornamental design for a night light, as shown and described.

DESCRIPTION

1. Night light

1.1 : Front

1.2 : Back

1.3 : Left

1.4 : Right

1.5 : Top

1.6 : Bottom

1.7 : Perspective

Figs. 1.1 to 1.7 are drawings showing of the night-light; the present product is used for lighting.

The broken line showing in the drawings is included for the purpose of illustrating portions of the night light and forms no part of the claimed design.

1 Claim, 7 Drawing Sheets(56)
